UNITED STATES PATENT OFFICE.

GEORGE RIPLEY STETSON, OF NEW BEDFORD, MASSACHUSETTS, ASSIGNOR
TO HIMSELF AND THE MORSE TWIST DRILL AND MACHINE COMPANY,
OF SAME PLACE.

MACHINE FOR MAKING TWIST-DRILLS.

SPECIFICATION forming part of Letters Patent No. 312,401, dated February 17, 1885.

Application filed October 25, 1883. (No model.)

To all whom it may concern:

Be it known that I, GEORGE R. STETSON, of New Bedford, in the county of Bristol and State of Massachusetts, have invented certain 5 new and useful Improvements in Machines for Making Twist-Drills, of which the following is the specification.

My invention relates to the class of machines illustrated in Letters Patent No. 176,250, 10 and to improvements in such machines.

In my improved machine the gradually-expedited advance of the mandrel and blank, in order to obtain the increasing pitch or inclination of the groove, is secured by the action 15 of a suitably-formed cam impinging directly upon the mandrel itself, instead of, as in the patent referred to, upon radial roller-studs or other equivalent interposed devices between the face of the cam and that part of 20 the mandrel against which its action is brought to bear.

The drawings illustrate a machine of this construction, Figure 1 being an elevation, and Fig. 2 a section, in which a wedge-cam is employed, and Fig. 3 being a plan view of the cam and its operating-pinion. Figs. 4 and 25 5 are views in elevation and section, showing an eccentric in place of the wedge-cam.

The operating mechanism in all the drawings 30 is substantially like that shown in the granted patent above referred to. The wedge-cam may be conveniently constructed in the form of a parallelogram interiorly slotted, and provided upon one exterior side with a 35 rack, *a*, Fig. 3, by which motion is given to it when such a form of cam is used. I prefer to form the mandrel *B* at that portion of it exposed to the cam action with an annular boss having a partly-spherical contour, 40 which bears against the cam.

Instead of the sliding cam, I may use a rotating cam, *C*, with suitable operating-gearing, *c c*, as shown in Figs. 4 and 5. As the cam is caused, by means of the gears *c c* or 45 the pinion *b* and rack *a*, to act against the mandrel *B*, the graduated cam-face advances the mandrel which carries the drill *D* in direct proportion to the pitch of the cam, which,

in turn, is made to correspond to the required increased pitch in the drill, and the advance 50 of the mandrel being thus increased in speed as the cutting progress, there is a corresponding increase in the pitch of the drill, which increase in pitch it is the object of this machine to obtain.

For the more convenient return of the mandrel at the end of the cutting operation, I provide it with an extension, *E*, bearing against and compressing a spring, *e*, as the mandrel advances, which compressed spring, as will 60 be seen, acts to bring the mandrel back after its forward motion has ended.

The other parts of the machine present no substantial difference from those shown in the Letters Patent above referred to. The 65 mandrel is guided in its forward and back motions by its bearings in the gears, which are splined to it to permit of its passage through them.

From the foregoing it will be perceived that 70 the structure or organization of my improved twist-drill machine is materially simplified; that I dispense not only with the friction-rollers shown in the said patent, but also with the disk provided for carrying the friction-rollers, and transfer the cam action directly 75 to the mandrel, instead of having it communicated indirectly through expensive intermediate appliances. The friction-rollers and the disk in such a machine as the patented one referred to have in practice to be made strong 80 in order to resist the strains applied, and they are consequently expensive. They are also liable to get out of order, and constitute an unnecessary element to the practical efficiency 85 of the machine. Besides this, it is necessary to have more than one bearing upon the cam where such disk and friction-rollers are employed, as illustrated in said patent, in order to give the proper direction of force of the 90 cam action. This results in the necessity of having what is really a triple cam, equivalent practically to three wedges; otherwise a proper balance of force could not be obtained.

It will be seen that in order to accommodate 95 the change and simplification above set forth I

have very greatly modified the construction as well as the relations of the cam applied to the mandrel, and that the result is a materially cheaper, simpler, more efficient, and 5 every way superior machine.

I claim—

In a machine for making increased twist-drills, the combination of a mandrel to advance and rotate the drill-blank, and a suit-10 ably-formed cam acting directly against the

mandrel, whereby the advance of the latter is accelerated as the cutting progresses to increase the pitch of the drill.

In testimony whereof I have hereunto subscribed my name this 18th day of October, A. 15 D. 1883.

GEORGE RIPLEY STETSON.
